UNITED STATES PATENT OFFICE.

LOUIS M. POTTS, OF BALTIMORE, MARYLAND, ASSIGNOR, BY MESNE ASSIGNMENTS, TO
AUSTIN McLANAHAN, OF BALTIMORE, MARYLAND.

PERFORATING-MACHINE.

1,018,519.

Specification of Letters Patent.

Patented Feb. 27, 1912.

Original application filed July 6, 1905, Serial No. 268,494. Divided and this application filed December 1, 1909. Serial No. 530,793.

To all whom it may concern:

Be it known that I, LOUIS M. POTTS, a citizen of the United States, residing at Baltimore city, in the State of Maryland, have invented certain new and useful Improvements 5 in Perforating-Machines, of which the following is a specification.

The primary object of this invention is the production of a machine for preparing 10 forms, webs or fillets for controlling automatic telegraph transmitters, linotypes or other mechanisms adapted to be controlled by such devices.

A further object of the said invention is 15 the production of a machine of the above character which will impress apparatus controlling impressions such as perforations, embossments or their equivalents in line to line form on a sheet of paper, or other suitable material, the intelligence represented 20 by said impressions reading from the end of one line to the commencement of the next succeeding line.

A further object of the said invention is 25 the production of a machine of the above character which, in addition to producing code impressions of the kind above described, also impresses on the same sheet therewith printed characters corresponding 30 to the respective code impressions, and arranged in similar line to line formation.

Other objects of the said invention will more fully appear from the following detail description of my said invention.

The machine forming the subject of the 35 present application was originally shown, described, and claimed in an application for improvements in automatic telegraphs and the like filed by me July 6, 1905, Ser. No. 40 268,494, on which was granted December 7, 1909, Patent No. 942,844, and of which application the present one is a division.

In order to more fully describe my said 45 invention reference will be had to the accompanying drawings wherein,

Figure 1, represents one form of controlling device prepared with my improved machine; Fig. 2, a central vertical section partly in elevation of one form of the said 50 machine; Fig. 3, a top plan view of the same, showing the electric circuits whereby it is operated; Fig. 4, an enlarged development of the type-wheel of said machine; Fig. 5,

an enlarged fragmentary vertical section of 55 said typewheel and the punching device operated thereby; Fig. 6, a top plan view of the same, and Fig. 7, an enlarged sectional view of the auxiliary punching device for perforating the controlling form at the commencement of each line. 60

In the following description it will be assumed that the prepared form is intended to control an automatic telegraph transmitter. I shall first describe one of these forms and then describe the machine for preparing 65 them.

The form, as shown in Fig. 1, consists of a sheet or page of paper or other suitable material having thereon a plurality of impressions arranged in accordance with a 70 pre-selected code, and a printed or typewritten character corresponding to each code impression or combination of impressions representing such character. These code impressions may consist of perforations, embossments or any other forms of impression which will accomplish substantially the same result. The message is impressed on the blank in a series of horizontal lines as in ordinary writing, and when printed characters are used, the code impressions are arranged in a vertical line either directly above or below the printed character represented thereby. In the specific form herein shown the code impressions are in the form of small 75 perforations 1, and two of such perforations are combined, according to a code now to be described, to form a letter of the alphabet, numeral, or other symbol. The code herein described is substantially that of the Rowland system, described in one form in the Patent No. 713,497, to Henry A. Rowland, granted November 11, 1902, wherein eleven 80 circuits of a keyboard are combined two-and-two to effect a large number of combinations, each of which effects the transmission of a different signal. For the purpose of explaining how the perforations are arranged on the sending form according to 85 this code, let the form (Fig. 1) be divided by a series of imaginary horizontal parallel lines of four groups, indicated by the dotted lines lettered *a*, *b*, *c*, *d*; *e*, *f*, *g*, *h*, *i*, *j* and *k*, and let each of these groups of imaginary 90 lines correspond to a line of matter to be transmitted. Then for each character in

95 100 105

said line of matter there will be two perforations located upon two such horizontal lines. For example, the code arrangement of perforations to produce the letter "A" 5 consists of a perforation on the horizontal line *b* and a perforation located directly thereunder on the horizontal line *f*. The code arrangement for the letter "J" consists of two perforations located one above the 10 other on the *c* and *i* lines, respectively, and so on. Each vertical line of perforations forming a combination is spaced a suitable distance horizontally from the next adjacent combination.

15 At the same time that the form is perforated, the character or symbol representing the combination of perforations may be printed or typewritten thereon, preferably directly above or beneath the code perforations. In the specimen illustrated in Fig. 1, 20 these printed characters are directly beneath the code perforations. In this way the message may be easily read and mistakes readily detected before transmission.

25 The form shown is provided with a series of auxiliary perforations 2, along one of its edges, preferably opposite the commencement of each line of printed matter. These perforations, register with retaining devices on the transmitting apparatus for imparting motion to the form, and act also as a means for accurately placing the forms in the transmitter each time in the proper position. A form of the machine for preparing these controlling devices is shown 30 most clearly in Figs. 2 to 7. The spacing, lining, inking or ribbon mechanisms of this machine may be substantially the same as shown in the Patents Nos. 290,419 or 501,504, 35 to J. B. Hammond, or of other forms, such parts being omitted from the drawings as unnecessary to a full understanding of my present invention.

In the machine illustrated, 3 represents 40 the paper carrying carriage, having the paper holding rollers 4, 5 journaled in the end brackets 6, 7, 8, a series of vertically movable stop pins arranged in the arc of a circle and supported by stationary frames 45 9 and 10 through which they pass. Each of these pins is provided with a shoulder or lug 11 arranged to rest on the lower frame 10, and above this lug, a spiral spring 12 bearing at one end on such lug and at its 50 upper end against the lower face of the frame 9. The pins 8 are therefore normally forced downward under the tension of said springs. Each pin 8 is located directly 55 above a pivoted key lever 13, in such manner that by the depression of a key the stop pin corresponding thereto will be raised vertically, as in the Hammond machine 60 above referred to.

The type-wheel 14 is mounted fast upon 65 the upper end of a vertical spindle 15 ar-

ranged to turn on its vertical axis. Made fast to the type-wheel spindle is an arm 16 having attached thereto and insulated therefrom as at 17, a metal arm 18, the free end of which is arranged to pass over the top of the frame 9 over the upper ends of the stop pins. Rotary motion is imparted to the type-wheel through its spindle by means of two electromagnets or solenoids 19 and 20, the armatures or movable cores 21 and 22 of which are secured each to one end of two horizontally slideable rods 23, 24, made fast at their inner ends to a rack 25 which engages a pinion 26 mounted fast on the type-wheel spindle. The arm 18 is returned to its initial position by springs 23', 24' upon the rods 23, 24, said springs being accurately balanced against each other by means of the adjusting nuts 23'' and 24''.

70 The type-wheel is provided with a type-flange 27, and an upwardly extending flange or cylindrical portion 28 of smaller diameter than the type-flange. On the surface of this portion 28 is formed a plurality of 75 small cams 29, arranged as shown most clearly in the development of the type-wheel, Fig. 4. These cams are arranged in combinations of two in a vertical line above each character on the type-wheel and lie in 80 eleven horizontal rows, just as in the case of the perforations of the sending form, so that in line with each character on the type-wheel there will be a different combination of cams. The object of these cams is to operate a series of pins in certain combinations whereby a different combination of 85 perforations may be made in the sending form. For this purpose, I secure rigidly 90 to the frame of the machine a block 30, having therein a vertical row of eleven chambers (see Fig. 5), each of said chambers opening through one side of the block by 95 apertures 32 of smaller diameter than the chambers. In each of these chambers is 100 mounted a pin 33 having a shoulder or fixed collar 34 thereon arranged to engage one 105 end of the chamber under the tension of a coil spring 35 on the pin. One end of each 110 of these pins extends through the block 30 into close proximity to the surface of the 115 cam portion of the type-wheel, while the other end extends into a bushing 36 in the other end of the chamber. These pins are 120 so arranged and spaced that one will register with, or be in line with, each horizontal 125 row of cams on the type-wheel, so that as each combination of cams in a vertical line comes in front of the vertical row of pins, a different combination of two such pins 130 will be engaged by said cams and moved laterally against the tension of their springs 35, and caused to project (as shown in Fig. 5) beyond the face of the block 30. Located directly in front of this block 30, and

at a sufficient distance therefrom to allow the form or paper to be prepared to pass between them, is the combined platen and perforating block 37. This consists of a vertically elongated block having a vertical row of horizontal openings 38 therethrough, each of which is located exactly in line with a corresponding pin 33. The openings 38 are of substantially the same shape as the cross-section of said pins, though slightly larger in diameter, to receive them. On the lower end of the block 37 is the type platen 39 adapted to be arranged in line with the type-flange.

The block 37 is carried by two rods 40, which pass loosely through the magnet yoke 41 and rear cross pieces 42 of a supporting bracket 43 made fast to a rigid upright 44. These rods 40 carry at their ends opposite said block 37, an armature 45 which lies in front of the poles of two electromagnets 46 made fast at their outer ends to a preferably nonmagnetic supporting bracket 43, as shown most clearly in Fig. 3. These magnets are arranged when excited to attract the armature 45 against the tension of springs 47 carried on the rods 40, and to thus send the block 37 forward. This operation causes the platen 39 to send the blanks (see Fig. 5) against the type. At the same time, the blanks 48 will be sent by the block 37 against the combination of pins at that instant sent forward by the cams. The force of the block 37 is sufficient to drive said pins through the paper into the openings 38, thus perforating the same in the desired combinations. The movement of the armature forward is adapted to bring a contact 49 in electrical connection with the frame of the machine, into engagement with a stationary insulated contact 50.

Arranged beneath the key levers 13 are two insulated conductors 51 and 52, the latter of which is arranged to be brought into electrical connection with all of the key levers on the right of the insulation 53, when said levers are depressed as in operation, and the other of said conductors is arranged to be similarly brought into electrical connection with the key levers on the left of said insulation, each of said key levers being, for this purpose, provided with a small contact spring 54, though this contact spring may be dispensed with and the key levers made to engage the conductors 51 and 52 direct.

In addition to the above described punching arrangement, I provide an auxiliary punching device arranged to perforate the telegraph form once near one edge as shown at 2 in Fig. 1, at the commencement of every line. This auxiliary punching device operates automatically and consists of two punching members 55 and 56 mounted rigidly near one end of the carriage and sepa-

rated by a sufficient space to allow the paper or telegraphic form to pass between them. The member 55 consists of a metal block or arm made fast as at 57 to the end frame 6 of the carriage. This member is provided, as shown most clearly in Fig. 7, with a chamber 58 in which is located a punching pin 59 having a collar 60 fast thereon adapted to engage the walls of said chamber. This pin extends into an opening 61 through the front of the block, of smaller diameter than the chamber 58. Surrounding the pin 59 and between the collar 60 and the front wall of the chamber 58 is a spiral spring 62 which is held under tension by the bushing 63 screwed into the chamber on the other side of the collar 60, the pin extending through and out beyond said bushing as shown. Pivoted between two lugs 64 on the member 55, is a lever 65 having an arm 66 adapted to engage the end of the pin 59. A larger arm 67 provided with a lug or pin 68 is arranged to engage a stop at a certain point of the carriage travel. This stop is shown in the present case as an adjustable screw 69 carried by the lug 70 on the frame 43. This stop 69 is so located that when the carriage reaches the end of its travel, the pin 68 will engage the head of said screw 69 and cause the lever to send the perforating pin 59 forward. Located exactly in line with the pin 59 is an opening 71 in the member 56 arranged to receive said pin when sent forward as described. (See Fig. 7). This member 56 may be made fast to the carriage in any desired way, but must be held at all times in accurate alinement with the member 55.

The electromagnets 19, 20 and 46 are connected to and disconnected from a source of current supply indicated by the supply mains A and B, through the medium of three relays 72, 73 and 74, the electric circuits of which may be readily traced from the following description of the operation of the machine: Let A and B represent respectively the positive and negative wires of a direct current circuit of a proper voltage, and let 13 represent any of the plurality of keys depressed to print a letter or other character. Upon the depression of this key to the proper extent, an electric circuit will be completed which may be traced as follows: from the positive wire A through wire 75, coil 76 of relay 74, wire 77, contact strip 52, key lever contact 54, key lever 13, pin 8, frame of the machine and thence by wire 78 back to the negative main B. The circuit thus completed causes the tongue of relay 74 to be sent against its forward contact 79, and this completes a second circuit which may be traced as follows: from positive main A to wire 80, coil of magnet 20, wire 81, relay contact 79, tongue of relay 74, wire 82 and negative main B. The circuit

thus completed causes current to energize the magnet 20 which draws in its core 22, thereby rotating the type-wheel and arm 18. This arm 18 stops the type-wheel in the proper place by engaging the pin 8 sent upward into its path by the operation of key lever 13, and when the arm 18 thus engages a pin 8 another electric circuit is completed which may be traced as follows: from the positive main A to wire 83, coil 84 of relay 72, wire 85 to insulated arm 18, pin 8, frame of the machine back by wire 78 to the negative main B. This circuit sends current through the coil 84 of relay 72, and causes that relay to send its tongue against its forward contact 86, and this completes a circuit through the coils of the magnets 46 which may be traced as follows: from positive main A to wire 83, tongue of relay 72, contact 86, coils of magnets 46, wire 87 back to the negative main B. The magnets 46 thus become energized, attract their armature 45, and send the combined punch member and platen 37 forward thus simultaneously 25 punching the proper combination of code perforations in the blank and printing the character corresponding thereto. This movement of the armature 45 causes the movable insulated contact 49 (see Fig. 2) to be brought into engagement with the fixed contact 50 in electrical connection with the frame of the machine, thus completing a circuit which will restore all of the relay tongues to their initial positions and break 30 the circuits through the operating magnets. This restoring circuit may be traced as follows: from the positive main A to wire 88, coil 89 of relay 74, wire 90, coil 91 of relay 73, wire 92, coil 93 of relay 72, insulated bracket 50' carrying contact 50, contacts 50 and 49 to the frame of the machine, and thence by wire 78 back to the negative main B. Current through this circuit sends the tongues of all of the relays against their 35 back stop contacts thus breaking the circuits established through the magnets 20 and 46, restoring the parts to their initial positions. The armatures 21 and 22 and the type-wheel are returned by the springs 23' and 24'. This is the complete operation 40 for printing a character and perforating the blank or form when any of the key levers on the right of the insulation 53 (Fig. 3) separating the contact strips 51 and 52 are operated. The operation for the keys on the 45 left of said insulation is exactly the same, except in the latter case the key levers make contact with the strip 51 instead of strip 52; the relay 73 takes the place of the relay 74, and the magnet 19 the place of the magnet 20.

When the end of a line is reached, the pin 68 on the lever arm 67 of the auxiliary punching device engages the stop 69, being sent thereagainst by the force of the car-

riage in its travel, and this causes the pin 59 to punch a hole in the form corresponding to a hole 2, in Fig. 1.

While I have herein shown and described one specific embodiment of my said invention, I do not wish to be understood as limiting myself to the specific construction shown.

What I do claim as my invention is:

1. A machine for preparing page blanks 75 for controlling automatic telegraph transmitters and the like, comprising a plurality of punches, mechanism whereby the blank being punched and the punches are relatively movable transversely of the blank, 80 and also in a direction at right angles thereto to form successive lines of impressions on said blank in which the information reads from the end of one line to the commencement of a succeeding line, and mechanism to 85 select and operate the desired punches to form a given code impression.

2. A machine for preparing page blanks 90 for controlling automatic telegraph transmitters and the like, comprising a plurality of punches, mechanism whereby the blank being punched and the punches are relatively movable transversely of the blank, and also in a direction at right angles to said transverse movement to form successive 95 lines of impressions on said blank in which the information reads from the end of one line to the commencement of a succeeding line, a plurality of keys greater in number than said punches, and means controlled by 100 said keys to select and operate the desired punches to form a given code impression.

3. The combination with a typewheel, of a series of perforating pins movable relative thereto, means on said typewheel to operate 105 a different combination of said pins for each character, on said typewheel, perforating mechanism coöperating with said pins, means to operate with said typewheel to print the characters thereon on a sheet, and means to simultaneously operate said perforating mechanism to cause the same to impress a combination of perforations on said sheet corresponding to the characters printed.

4. A perforating machine, comprising a plurality of character keys, a plurality of punches of lesser number than said keys, a plurality of type corresponding in number to said character keys, selective mechanism controlled by said character keys and adapted to simultaneously select a combination of said punches and the corresponding type, means coöperating with said selected punches to perforate a sheet of material, 125 and printing means adapted to coöperate with said type to print the selected character on said material.

5. A perforating machine, comprising a plurality of character keys, a plurality of 130

- 5 punches of lesser number than said character keys, means controlled by said character keys to select a given combination of said punches for the respective keys operated, and power operated means controlled by said selecting means to operate the punches selected. 11. A machine for preparing blanks for controlling automatic telegraph transmitters and the like, comprising a plurality of movable punches, adapted to impress code characters on said blank, a movable member having lugs thereon arranged in code formation to select and actuate said punches, character selecting mechanism determining the combinations of said lugs to be brought into action for a given character, and power operated means controlled by said character selecting mechanism to actuate said lug carrying member. 70
- 10 6. A perforating machine, comprising a plurality of character keys, a plurality of movable stops operated by said keys, a rotary body having a plurality of cams thereon arranged in combinations, a plurality of punches arranged for operation by said cams, electrical means to rotate said cam carrying body, and electric circuits controlled by said keys for controlling the operation of said electrical operating means. 15 7. A machine for preparing blanks for controlling automatic telegraph transmitters and the like, comprising a plurality of punches, a member having code arranged lugs adapted to actuate a given combination of said punches for producing a given code character, power mechanism for operating said punch actuating member, a plurality of character keys of greater number than said punches, and means controlled by said character keys and controlling the operation of said punch actuating member by 20 30 8. A machine for preparing blanks for controlling automatic telegraph transmitters and the like, comprising a plurality of punches, mechanism having code arranged lugs adapted to select and actuate a given combination of said punches for a given character, power mechanism for operating said punch selecting and actuating mechanism, a plurality of character keys greater in number than said punches, and means controlled by said keys to control the operation of said punch selecting and actuating mechanism by said power mechanism. 35 40 9. A machine for preparing blanks for controlling automatic telegraph transmitters and the like, comprising a plurality of punches, a type carrying member having code arranged lugs thereon adapted to select and operate a combination of punches 45 50 55 60 65 70 75 80 85 90 95 100 105 110 115 120 125 130 for producing a code character corresponding to said type, power mechanism for operating said member, a plurality of character keys of greater number than said punches, and means controlled by said character keys and controlling the operation of said type carrying member by said power mechanism. 10. A machine for preparing blanks for controlling automatic telegraph transmitters and the like, comprising a plurality of punches, punch selecting mechanism comprising a plurality of movable members, a plurality of keys greater in number than said punches, means controlled by said keys individually for imparting movement to said members to effect the selection of the desired punches, and power operated means coöperating with said punches to impress code characters on said blank. 11. A machine for preparing blanks for controlling automatic telegraph transmitters and the like, comprising a plurality of movable punches, adapted to impress code characters on said blank, a movable member having lugs thereon arranged in code formation to select and actuate said punches, character selecting mechanism determining the combinations of said lugs to be brought into action for a given character, and power operated means controlled by said character selecting mechanism to actuate said lug carrying member. 12. A machine for preparing blanks for controlling automatic telegraph transmitters and the like, comprising a plurality of movable punches, a movable type carrying member having lugs thereon arranged in code formation to correspond to the characters represented by said type and adapted to select and actuate said punches, character selecting mechanism determining the type and lugs to effect a given impression, and power operated means controlled thereby to actuate said type carrying member. 13. In a machine for preparing blanks for controlling automatic telegraph transmitters and the like, the combination with an angularly movable wheel or shuttle, having upon its periphery code arranged projections adapted to impress apparatus controlling code characters on said blank extending thereinto, means coöperating with said projections to effect said impressions, a plurality of keylevers one for each code character, and means controlled thereby to rotate said wheel and operate its coöperating means for effecting said impressions. 14. In a machine for preparing blanks for controlling automatic telegraph transmitters and the like, the combination with an angularly movable wheel or shuttle, having upon its periphery printing type and code arranged projections, the latter adapted to impress apparatus controlling code characters on said blank, means coöperating with said type to effect the printing, and coöperating with said projections to effect said code impressions, a plurality of keylevers corresponding in number to said characters, and means controlled thereby to rotate said wheel or shuttle and operate said printing and code impressing means. 15. In a machine for preparing blanks for controlling automatic telegraph transmitters and the like, comprising a type carrying member mounted for angular movement, projections on said member adjacent said type and arranged in code formation corresponding to the characters represented by the said type, a striker provided with means

to coöperate with said type and with said projections to simultaneously print a character and impress apparatus controlling code impressions on said blank, a plurality 5 of character keys corresponding respectively to said type, and means controlled by said keys to operate said striker and rotate said type carrying member.

16. A machine for preparing page blanks 10 for controlling automatic telegraph transmitters and the like, comprising a plurality of punches, mechanism to select and operate said punches, a plurality of keys controlling the selection of said punches, a carriage to 15 carry the page blank being punched, the said carriage being shiftable laterally with respect to said punches, and provided with means to shift said blank thereon transversely to its lateral movement to form successive lines.

17. A machine for preparing page blanks 20 for controlling automatic telegraph transmitters and the like, comprising a plurality of punches, mechanism adapted to select and 25 actuate a given combination of said punches for a given character, power mechanism for operating said punch selecting and actuating mechanism, a plurality of character keys greater in number than said punches, means 30 controlled by said keys to control the operation of said punch selecting and actuating mechanism by said power mechanism, and mechanism for effecting relative movement between said punches and the page 35 blanks being punched both transversely of said blanks and in a direction at right angles thereto to form spaces between successive

characters produced by said punches, and also to form lines of such characters in which the information reads from the end of one 40 line to the commencement of a succeeding line.

18. In a machine for preparing page blanks for controlling automatic telegraph transmitters and the like, comprising a type 45 carrying member mounted for angular movement, projections on said member adjacent said type and arranged in code formation corresponding to the characters represented by the said type, a striker provided 50 with means to coöperate with said type and with said projections to simultaneously print a character and impress apparatus controlling code impressions on said blank, a plurality 55 of character keys corresponding respectively to said type, means controlled by said keys to operate said striker and rotate said type carrying member, and mechanism for effecting relative movement between said punches and the page blanks being punched 60 both transversely of said blanks and in a direction at right angles thereto to form spaces between successive characters produced by said punches, and also to form lines of such characters in which the information reads 65 from the end of one line to the commencement of a succeeding line.

In testimony whereof I affix my signature in presence of two witnesses.

LOUIS M. POTTS.
